[73] Assignee: **Matsushita Electric Industrial Co., Ltd., Osaka, Japan**

[**] Term: **14 Years**

[57] CLAIM

[21] Appl. No.: **28,496**

The ornamental design for a remote controller for television receiver, as shown.

[22] Filed: **Sep. 16, 1994**

DESCRIPTION**[30] Foreign Application Priority Data**

Mar. 16, 1994 [JP] Japan 6-6993

[52] **U.S. Cl.** **D14/218**

[58] **Field of Search** D10/104, 106; D13/168; D14/124, 217, 218, 299; 348/734; 455/151.1-151.4, 352-355

FIG. 1 is a perspective view of the rear, top and right side of a remote controller for television receiver showing our new design;

FIG. 2 is a top plan view thereof;

FIG. 3 is a rear elevational view thereof;

FIG. 4 is a front elevational view thereof;

FIG. 5 is a right side elevational view thereof;

FIG. 6 is a bottom plan view thereof; and,

FIG. 7 is a left side elevational view thereof.
